WALKING STILT

George G. Young, 5906 N. Waterbury Road,
Des Moines, Iowa 50312

Filed Dec. 13, 1972, Ser. No. 314,701

Term of patent 14 years

Int. Cl. D21—01

U.S. Cl. D34—14 E

FIG. 1 is a front perspective view of a walking stilt showing my new design;

FIG. 2 is a rear perspective view thereof;

FIG. 3 is a top plan view thereof;

FIG. 4 is a bottom plan view thereof; and

FIG. 5 is an enlarged bottom plan view of the step portion, the stilt having been omitted for convenience of illustration.

I claim:

The ornamental design for a walking stilt, substantially as shown and described.
